(57) **CLAIM**

We claim the ornamental design for an audio control device, as shown and described.

DESCRIPTION

FIG. 1 is a front, bottom perspective view of an audio control device showing the claimed design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a front, bottom perspective view showing the claimed design in a second usage state;
FIG. 9 is a rear, bottom perspective view of the claimed design; and,
FIG. 10 is a rear, bottom perspective view of the claimed design in a third usage state.
The broken lines in the figures represent portions of the audio control device that form no part of the claimed design.

1 Claim, 9 Drawing Sheets
